VOLTAGE-REGULATING EQUIPMENT FOR
PRECIPITATORS OR THE LIKE

Myron J. Brown, Wilkinsburg, Pa., assignor to
Westinghouse Electric & Manufacturing Com-
pany, East Pittsburgh, Pa., a corporation of
Pennsylvania

Application October 26, 1940, Serial No. 362,944

16 Claims. (Cl. 171—119)

My invention relates to novel current-responsive means and novel voltage-regulating means for electrostatic smoke-precipitators or other electrical load-devices having a certain desirable operating-range in which transient flashes or current-increases occur at a certain predetermined rate at the highest safe operating-voltage which should be applied to the load-device.

The efficiency of an electrostatic precipitator depends upon its applied-voltage; and the amount of voltage which can feasibly be applied to the precipitator is limited by the tendency of the precipitator to arc over, or to become short-circuited by means of a concentrated-current arc which hangs on until the precipitator-voltage is suitably reduced. In some precipitator-installations, particularly where rather high ballast-resistances are utilized in series with the circuit, and where fairly high arc-extinguishing draft-velocities of the treated gases are utilized, it has been found that there is an operating-range, at voltages just short of the voltage which will produce series arcing, in which the precipitator will exhibit the phenomenon of spitting or flashing or flashovers, resulting in momentary or transient current-increases which do not hang on, like an arc-current, but which heal themselves and return again to normal-current conditions, the frequency and intensity of such spitting increasing as the applied-voltage approaches closer and closer to the voltage at which arcing occurs.

It should be understood that both the flashovers and the arcings of the precipitator are random phenomena, occurring at widely variant intervals even under seemingly identical conditions, and of course varying with the nature and size of the smoke-particles or other foreign matter contained in the draft of gases passing through the precipitator, and also varying from other causes. Because of the random nature of the spitting phenomenon, it is necessary, in order to keep the precipitator operating at its highest permissible voltage, to reduce the applied voltage whenever the frequency or intensity of the spitting-impulses becomes too high, and to keep increasing the voltage, so as to slowly advance it toward a higher value, whenever the rate of occurrence of the spittings falls off below a predetermined number of spittings in any suitable time-interval.

In many electrical smoke-precipitator applications, the maximum permissible precipitating-voltage which will not produce arcing, or too frequent arcing or short-circuiting of the precipitator, is variable from time to time, depend-

ing upon a number of factors, including the cleanliness of the precipitator, the atmospheric conditions, and the smoke conditions. In order that the precipitating equipment may always be operated at its highest permissible voltage, and hence at its maximum efficiency, it is frequently desirable to provide means for automatically varying the voltage which is applied to the precipitator so as to produce harmless momentary or transient flashings at a predetermined average rate which experience has shown to be feasible, the procedure being to keep raising and lowering the precipitator-voltage as may be necessary to maintain the rate of flashing within prescribed limits. My invention relates to novel and improved means for accomplishing such a purpose.

The objects of my invention also include certain specific means and combinations, including (1) the use of a slowly moving timing-device or relay, having front and back contacts, and having a drifting rate of movement, in their direction, which is substantially independent of the electrical conditions of the precipitator, or the amount of precipitator-current, whenever the timing-device is moving at all, (2) specifically the use of a line-energized slow-type voltage-relay for the above-described timing device, (3) the use of current-responsive means which responds to instantaneous or momentary values of the magnitude of the current, regardless of the rate of change of the current as in some previous devices, (4) and specifically the use of a cold-cathode grid-glow tube with its grid energized responsively to the precipitator-current, as the specific current-responsive means referred to.

With the foregoing and other objects in view, my invention consists in the apparatus, systems, combinations, methods and parts hereinafter described and claimed, and illustrated in the accompanying drawing, wherein:

Figure 1 is a diagrammatic view of the essential features of an electrostatic precipitator-equipment embodying my invention in a simple form of embodiment for illustrating the essential principles of the invention, without the distraction of numerous details which are known to the skilled workers of the art and which do not constitute any essential part of my present improvements; and

Fig. 2 is a diagrammatic view of a portion of the circuit, illustrating a modification.

In Fig. 1, my invention is illustrated as being applied to the control of an electrostatic precipitator which is diagrammatically represented

as comprising a grounded conducting duct or chimney 3, through which passes one or more precipitating-wires or electrodes 4, which are energized, through a mechanical, rotating rectifier 5, from the high-voltage secondary-winding 6 of a step-up transformer 7. The primary winding 8 of the precipitator-transformer 7 is connected to a supply-circuit 9 which is energized from a single-phase supply line L₁—L₂ through a ballast-resistor 11 and a voltage regulating means which is illustrated in the form of an induction-regulator 12 which is adjusted, either in a voltage-raising direction or in a voltage-lowering direction, by means of an alternating-current motor M having a raising winding RW and a lowering-winding LW.

The energization of the regulator-motor M, in either the raising or lowering direction, is under the control of a timing-means having a fairly constant timing-interval which is substantially independent of the operating-conditions of the precipitator, such timing-means being illustrated in the form of a slow-moving voltage-relay V such as a contact-making instrument of the induction-disc type, having back-contacts 15 and front or "make" contacts 16. The voltage-relay V has biasing-means, illustrated in the form of a spring 17, tending to return the movable contact-element 18 to its non-actuated position in engagement with the back-contacts 15, and it is also provided with an actuating-coil 19 which, when sufficiently electrically energized, so that its operating-force overpowers the pull of the biasing spring 17, causes the movable element 18 to slowly move to its actuated position in engagement with the front-contacts 16. The actuating-coil 19 of the voltage-relay V is energized from the line L₁—L₂, through a variable resistor 20 by means of which the operating-speed or forward-moving speed of the voltage-relay may be adjusted.

Suitable means are provided for causing the biasing-action of the biasing spring 17 to predominate over the actuating-force of the electrically energized coil 19 at certain times, as will be subsequently described. The illustrated means for causing the biasing spring to predominate includes a short-circuiting circuit 21 around said actuating-coil 19, said short-circuiting circuit including a variable resistor 22 for adjusting the resetting speed or backwardly moving speed of the voltage-relay V. The short-circuiting circuit 21, around the actuating-coil 19 of the voltage-relay V, is completed by the closure of either one of two relay-contacts 23 or 24, as will be subsequently described.

In order to avoid the necessity for utilizing voltage-relay contacts 15 and 16 which are sufficiently heavy to control the regulator-motor M, I have shown, as a matter of practical convenience, the utilization of two auxiliary relays 25 and 26 which are respectively energized from the back and front-contacts 15 and 16 of the voltage-relay V. The auxiliary relay 25 is a voltage-lowering relay having a make-contact 27 which is utilized to energize the lowering-winding LW of the regulator-motor M. The auxiliary relay 26 is a voltage-raising relay having a make contact 28 which is utilized to energize the raising-winding RW of the regulator-motor M. A capacitor 29 is connected across the terminals of the two motor-windings LW and RW to obtain reversing operation with a single-phase motor, in a manner which is known in the art.

The voltage-raising relay 26 also carries the

normally open contact 24 which is utilized for the purpose of completing the short-circuiting circuit 21—22 around the operating-coil 19 of the voltage-relay V. The object of this relay-contact 24 is merely to reduce the speed at which the voltage of the induction-regulator 12 is increased, this result being accomplished by "inching" the regulator-motor M in the voltage-raising direction, instead of continuously energizing the voltage-raising winding RW thereof and letting the motor run continuously as long as the voltage-relay front-contact 16 is closed. This regulator-inching means, in the form of an anti-hunting contact 24, is a known feature in the art, and is illustrated only because it is usually, though perhaps not universally, desirable, provided that the regulator-voltage is not raised too fast.

In order to cause the voltage-relay V to reset, or to move in the backward direction under the influence of the biasing spring 17, it is necessary to provide some means for closing the relay-contact 23 and keeping it closed for a sufficiently long time or times to permit the movable contact-element 18 of the voltage-relay to drift back from its front-contact position 16 to its back-contact position 15. I have provided a novel means for effecting this purpose, utilizing a cold-cathode grid-glow tube 31 having an anode 32, a grid 33 and a cathode 34. This tube or space-current arcing-device 31 has the property of "breaking down" or glowing or becoming conductive or arcing across its anode-cathode space, only when the starting control means or grid 33 is made sufficiently positive with respect to the cathode 34, for any given anode-cathode applied-voltage within the voltage-rating of the tube, and the tube has the further property, once it has "broken down" by the glowing of the grid, of maintaining its glowing or arcing or conducting condition, independently of the subsequent condition of said starting control means, until the applied voltage is interrupted or very materially reduced by some external or extraneous means.

In order to utilize this self-locking or current-maintaining property of the grid-glow-tube 31, I provide a suitable direct-current or unidirectional-current energizing-source in the anode-cathode circuit thereof, said source being illustrated in the form of a full-wave rectifier or rectifier-bridge 36 having one diagonal energized across the alternating-current supply-line L₁—L₂, so that the other diagonal of the bridge constitutes the direct-current terminals (+) and (—). The direct-current output-terminals (+) and (—) of the rectifier-bridge 36 are shunted by a bypassing capacitor 37 for the purpose of smoothing the direct-current voltage. The anode-cathode circuit of the grid-glow tube 31 includes the operating coil 38 and a back-contact 39 of a short-time relay 41, said anode-cathode circuit being traceable from the positive terminal (+) through the coil 38 and the contact 39 to the anode 32, and thence from the cathode 34 to the negative terminal (—).

The short-time relay 41, in addition to carrying the back-contact 39, also preferably carries a second back-contact 42, and also the previously described make or front-contact 23 which short-circuits the operating-coil 19 of the voltage-relay V through the adjusting resistor 22 whenever the short-time relay 41 is in its actuated position. The second back-contact 42 of the short-time relay 41 is utilized to energize a bypassing capacitor 43 in shunt-circuit relation to the operating-winding 38 of said relay, with the result that,

when the grid-glow tube 31 "breaks down" or begins to glow and conduct current in its anode-cathode circuit, the first current which flows is utilized to charge the capacitor 43. At the first instant, the capacitor 43 takes all of the tube-current, none of it passing through the highly inductive relay-coil 38. The capacitor 43 charges at a predetermined rate limited by the amount of current which is supplied thereto through the rectifier-bridge 36 and the grid-glow tube 31, 10 and as said capacitor 43 charges, its short-circuiting effect upon the relay-winding 38 becomes smaller, so that the current is transferred to the relay-coil 38, thus finally causing the short-time relay 41 to "pick up" or move to its actuated position in which it opens its back-contacts 39 and 42 and closes its front-contact 23.

The two back-contacts 39 and 42 of the short-time relay 41 are bypassed by an adjustable resistor 44 in such manner that when the relay 41 is actuated, the back-contacts 39 and 42 being open, the variable resistor 41 is included in a capacitor-discharging circuit whereby the capacitor 43 discharges through said adjustable resistor 44 and the actuating-coil 38 of the short-time relay 41, the discharging-rate being controllable by adjusting the resistance 44. By this means, the energization of the short-time relay 41 is maintained for a certain brief time-interval after the actuation of the relay, thus maintaining said relay in its actuated condition for a short time-interval which, in general, is or may be somewhat longer than the time-delay which was introduced in the picking-up operation of the relay while the capacitor 43 was initially charging. The size of the capacitor 43 is usually chosen so that it will store enough current to keep the relay-coil 38 energized for an appreciable time-interval, and during this time, the front-contact 23 of the relay remains closed, so that the movable contact 18 of the voltage-relay V is drifting backward in its resetting direction, or toward its back-contact 15.

The initial breaking down or glowing of the grid-glow tube 31 is adjustably controlled in response to the current flowing in the alternating-current supply-circuit 9 of the precipitator. To this end, I have shown an ordinary current-transformer 46 in said supply-circuit 9, said current-transformer being utilized to energize a high-voltage or step-up transformer 47, which is loaded by means of a resistor 48 which thus develops a voltage-drop or potential which is proportional to the supply-circuit current. The resistor 48 is included in the grid-circuit of the grid-glow tube 31, said grid-circuit also serially including a high-resistance grid-resistor 49, and an adjustable potentiometer 51. The terminals of the potentiometer 51 are connected across the direct-current supply-circuit terminals (+) and (-), and an adjustable intermediate tap 52 of said potentiometer is included in the grid-circuit. The grid-circuit may thus be traced from the grid 33 of the grid-glow tube 31 through the resistors 49 and 48 to the adjustable intermediate potentiometer-tap 52, and thence through a portion of the potentiometer 51 to the negative source-terminal (-) which is also connected to the cathode 34 of the grid-glow tube 31.

In operation, the voltage-relay V is normally energized so that said relay "picks up" and closes its front or make-contact 16, thus energizing the voltage-raising relay 26 and causing the regulator-motor M to "inch" along in the voltage-raising direction, thus gradually or cautiously raising 70 75

the voltage applied to the precipitator 4. As the precipitator-voltage rises higher and higher, the frequency and the intensity of its spitting-operations increase. Whenever such spitting occurs, the supply-line current in the current-transformer 46 also increases, and when a sufficiently severe momentary or instantaneous current-value is obtained during a positive half-cycle, that is, during a half-cycle of the alternating-current supply during which a positive voltage-component is applied to the grid 33 by the resistor 48, this voltage-component, when added to the tapped voltage of the potentiometer 51, will exceed the critical starting-voltage of the grid-glow tube 31, causing a glow-discharge to occur between the grid 33 and the cathode 34, said glow-discharge immediately filling the tube so that the anode-cathode tube-circuit or space is broken down or made conductive by means of a glow-discharge between the anode 32 and the cathode 34. The relay-bypassing capacitor 43 then charges, and as it approaches its charged-condition, the current passing through the grid-glow tube 31 transfers to the operating-coil 38 of the short-time relay 41, causing said short-time relay 41 to pick up, opening its back-contacts 39 and 42, closing its front-contact 23.

The closure of the relay-contact 23 short-circuits or bypasses the operating-coil 19 of the voltage-relay V, causing the latter to drift toward its non-actuated position, first immediately or quickly opening its front-contacts 16, thus stopping the forward or voltage-raising movement of the induction-regulator 12, after which the movable contact-member 18 of the voltage-relay slowly moves between its two limiting positions in a direction toward the voltage-lowering contact or back-contact 15.

The relay-contact 23 which causes this backward drifting of the voltage-relay V remains closed for a predetermined brief time-interval which is controlled by the discharging-rate of the relay-bypassing capacitor 43, which is now being discharged through the relay-coil 38 in series with the adjustable resistor 44. The time-interval during which the short-time relay 41 remains energized, keeping the relay-contact 23 closed, is adjustable, by means of the adjustable resistor 44. The rate at which the voltage-relay V is drifting backwardly, during this time-interval, is also adjustable, by means of the adjustable resistance 22. By either or both of these means, it is possible to adjust the amount or distance through which the voltage-relay V drifts backwardly during the time-interval during which the short-time relay 41 remains in its actuated position, and this drifting-distance is usually chosen so that it takes more than one, or several, such time-intervals to cause the movable contact 18 of the voltage-relay V to move all the way back from its fully actuated position in contact with the make-contacts 16, to its fully retracted position in contact with its back-contacts 15.

At the termination of the delayed-action current-responsive impulse which is provided by the short-time relay 41, as just described, the short-circuit is removed from around the operating-coil 19 of the voltage-relay V, so that the movable element 18 of said voltage-relay starts drifting forward again, toward its front or make-contact 16. This forward-drifting speed is controllable by the adjustable resistor 20, and is preferably adjusted so that it is of the same order of mag-

nitude as the backward-drifting or resetting speed previously referred to.

If a second current-impulse of sufficient magnitude and polarity does not occur before the voltage-relay V closes its front-contacts 16, the regulator-motor M will start "inching" again in the voltage-raising direction, thus again slowly raising the voltage applied to the precipitator-wire 4. If, however, another current-impulse occurs, so as to check the forward drifting of the voltage-relay V before it closes its front-contacts 16 again, said voltage-relay will start drifting backward again, through another short time-period under the control of the short-time relay 41, and on this occasion the voltage-relay will drift back still further, closer to its back-contact 15, because it started to drift backwardly from an intermediate position between the two limiting contacts 15 and 16. When such current-responsive impulses occur at a sufficiently fast rate, the movable element 18 of the voltage-relay V will drift all the way back to its back-contact 15, thereby energizing the voltage-lowering winding LW of the induction-regulator motor M, thus quickly reducing the voltage which is applied to the precipitator. At the termination of the last current-responsive delayed-action or short-time impulse which caused a reduction of the precipitator-voltage, the voltage-relay V will again start to drift forward, opening its back-contact 15; and if the frequency of recurrence of the precipitator-flashings has now been sufficiently reduced, as a result of the reduction in the precipitator-voltage, the voltage-relay V will finally drift to its full-actuated position 16, starting all over again to slowly "inch" the regulator-motor M in the voltage-raising direction.

While I have described my invention in connection with certain relative time-intervals and drifting-times, and while I have referred to the current-response as a series of discrete responses to transient current-impulses, I wish it to be understood that the operation of my device is not altogether limited in these respects. It is to be noted, in particular, that I have provided means whereby a wide range of adjustment is readily possible, in regard to the choice of the various timing-intervals and drifting-speeds or periods. As an example, but not by way of limitation, it may be noted that my invention can be utilized in a precipitating system under such operating-conditions as to obtain from 6 to 20 snaps or flashings per minute, utilizing a voltage-relay V having a drifting-time of some 20 seconds, or between 10 seconds and 60 seconds, for a full swinging-movement of the movable contact-element 18 in either direction of movement, and utilizing a timing-relay 41 which has a relatively brief pick-up time, but which holds its make-contact 23 closed for a short-time interval of from 1 second to 5 seconds. These various time-intervals are indicated only by way of illustration; as my invention, in its broader aspects, is not limited thereto.

In Fig. 2, I have reproduced a portion of the circuit shown in Fig. 1, for the purpose of illustrating a slight variation, the principal variation being that the current-energized resistor 48 is utilized to energize the input-diagonal of an auxiliary rectifier-bridge 54. The output-diagonal of the rectifier-bridge 54 is connected in the grid-circuit of the grid-glow tube 31 in such polarity that a positive voltage-component is always applied to the grid 33, regardless of the direction of the alternating-current flow. In this manner,

the device is caused to be responsive to current-magnitudes of a predetermined value, regardless of whether they occur in the positive or negative half-wave of the alternating current.

5 In Fig. 2, I have also indicated, by way of example, the inclusion of the high-voltage or step-up transformer 47 directly in the supply-circuit of the precipitator, without the intermediary of the conventional current-transformer 46 which was shown in Fig. 1. The power-translating load-device, or relay-coil 38, in the anode-cathode circuit of the tube 31 is broadly so indicated in Fig. 2, as well as the circuit-interrupting contact or switching-device 39 which is utilized to open the anode-cathode circuit in order to interrupt a discharge of the grid-glow tube 31. Except as noted, the operation of the device shown in Fig. 2 is the same as that which has been outlined in connection with Fig. 1.

20 While I have illustrated my invention in two forms of embodiment which are at present preferred, I wish it to be understood that such illustration is only by way of illustration and not by way of limitation, and I wish it to be further understood that my illustration is in a greatly simplified form, which has been done in order to facilitate the understanding of the essential features or principles of my invention. I desire, therefore, that the appended claims shall be accorded the broadest construction consistent with their language.

I claim as my invention:

1. Voltage-regulating equipment for an electrical load-device having a desirable operating-range in which a predetermined rate of occurrence of predetermined, randomly recurrent, transient, voltage-responsive current-increases is maintained between predetermined limits, comprising a supply-circuit for said load-device, voltage-regulating means associated with said supply-circuit, means for obtaining discrete current-responses to said transient current-increases, means for prolonging said discrete current-responses for short predetermined times, said short predetermined times being less than the longest expectable time-interval between successive transient current-increases, a timing-device having two different operational conditions, means for normally causing said timing-device to change from a first one of its operational conditions to its second operational condition at a first predetermined speed which is substantially independent of the electrical conditions of said load-device, means responsive to each of said prolonged discrete current-responses for causing said timing-device to change in the opposite direction at a second predetermined speed which is substantially independent of the electrical conditions of said load-device, said first and second predetermined speeds being both so slow that said timing-device completes only a part of a complete change from one operational condition to the other during one of said short predetermined times, means for adjusting at least one of the factors determining the part of said complete change which is effected during one of said short predetermined times in at least one of the directions of change of said timing-device, means for making a lowering adjustment of said voltage-regulating means when said timing-device reaches its first operational condition, and means for making a raising adjustment of said voltage-regulating means when said tim-

ing-device reaches its second operational condition.

2. Voltage-regulating equipment for an electrical load-device having a desirable operating-range in which a predetermined rate of occurrence of predetermined, randomly recurrent, transient, voltage-responsive increases in the magnitude of the load-current is maintained between predetermined limits, comprising a supply-circuit for said load-device, voltage-regulating means associated with said supply-circuit, means quickly responsive to any and all increases in the magnitude of the load-current beyond a predetermined value for obtaining predetermined discrete current-responses, means for prolonging said discrete current-responses for short predetermined times, said short predetermined times being less than the longest expectable time-interval between successive transient current-increases, a timing-device having two different operational conditions, means for normally causing said timing-device to change from a first one of its operational conditions to its second operational condition at a first predetermined speed, means responsive to each of said prolonged discrete current-responses for causing said timing-device to change in the opposite direction at a second predetermined speed, said first and second predetermined speeds being both so slow that said timing-device completes only a part of a complete change from one operational condition to the other during one of said short predetermined times, means for adjusting at least one of the factors determining the part of said complete change which is effected during one of said short predetermined times in at least one of the directions of change of said timing-device, means for making a lowering adjustment of said voltage-regulating means when said timing-device reaches its first operational condition, and means for making a raising adjustment of said voltage-regulating means when said timing-device reaches its second operational condition.

3. Voltage-regulating equipment for an electrical load-device subject to transient current-increases randomly recurring at a rate and with an intensity dependent upon the voltage, comprising a supply-circuit for said load-device, voltage-regulating means associated with said supply-circuit, a timing-device having two different operational conditions, means for normally developing a first actuating-effect tending to change said timing-device from a first one of its operational conditions to its second operational condition at a predetermined speed which is substantially independent of the electrical conditions of said load-device, current-responsive transient-summarizing means for at times counteracting said first actuating-effect and developing a second actuating-effect tending to change said timing-device in the opposite direction at a current-responsive speed which is so slow, at times, as to require a plurality of transient current-increases to occur before the timing-device is completely changed from its second operational condition to its first operational condition, means for making a lowering adjustment of said voltage-regulating means when said timing-device reaches its first operational condition, and means for making a raising adjustment of said voltage-regulating means when said timing-device reaches its second operational condition.

4. Voltage-regulating equipment for an electrical load-device subject to transient current-increases randomly recurring at a rate and with an intensity dependent upon the voltage, comprising a supply-circuit for said load-device, voltage-regulating means associated with said supply-circuit, means quickly responsive to any and all increases in the magnitude of the current beyond a predetermined value for obtaining predetermined discrete current-responses, short-time means for insuring that each of said discrete current-responses shall last for at least a short predetermined time which is less than the longest expectable time-interval between successive transient current-increases, a timing-device having two different operational conditions, means for normally developing a first actuating-effect tending to change said timing-device from a first one of its operational conditions to its second operational condition, current-responsive means including said short-time means for at times counteracting said first actuating-effect and developing a second actuating-effect tending to change said timing-device in the opposite direction at a current-responsive speed which is so slow, at times, as to require a plurality of transient current-increases to occur before the timing-device is completely changed from its second operational condition to its first operational condition, means for making a lowering adjustment of said voltage-regulating means when said timing-device reaches its first operational condition, and means for making a raising adjustment of said voltage-regulating means when said timing-device reaches its second operational condition.

5. Voltage-regulating equipment for an electrical load-device subject to transient current-increases randomly recurring at a rate and with an intensity dependent upon the voltage, comprising a supply-circuit for said load-device, voltage-regulating means associated with said supply-circuit, a cold-cathode grid-glow tube, direct-current energizing-means for its anode-cathode circuit, means for developing a grid-biasing voltage responsive to the load-current of the load-device and for so applying said grid-biasing voltage to the grid of the grid-glow tube as to cause a glow therein upon the attainment of an instantaneous current-magnitude of a predetermined value in said load-device, timing-means responsive to the glowing of the grid glow tube for subsequently interrupting the glowing operation thereof after a short predetermined time, a timing-device having two different operational conditions, means for normally developing a first actuating-effect tending to change said timing device from a first one of its operational conditions to its second operational condition, current-responsive means including a response to the anode-cathode circuit of said grid-glow tube for at times counteracting said first actuating-effect and developing a second actuating-effect tending to change said timing-device in the opposite direction at a current-responsive speed which is so slow, at times, as to require a plurality of transient current-increases to occur before the timing-device is completely changed from its second operational condition to its first operational condition, means for making a lowering adjustment of said voltage-regulating means when said timing-device reaches its first operational condition, and means for making a raising adjustment of said voltage-regulating means when said timing-device reaches its second operational condition.

means when said timing-device reaches its second operational condition.

6. Voltage-regulating equipment for an electrical load-device having a desirable operating-range in which a predetermined rate of occurrence of predetermined, randomly recurrent, transient, voltage-responsive increases in the magnitude of the load-current is maintained between predetermined limits, comprising a supply-circuit for said load-device, voltage-regulating means associated with said supply-circuit, a cold-cathode grid-glow tube, direct-current energizing-means for its anode-cathode circuit, means for developing a grid-biasing voltage responsive to the load-current of the load-device and for so applying said grid-biasing voltage to the grid of the grid-glow tube as to cause a glow therein upon the attainment of an instantaneous current-magnitude of a predetermined value in said load-device, timing-means responsive to the glowing of the grid-glow tube for subsequently interrupting the glowing operation thereof, a timing-device having two different operational conditions, means for normally developing a first actuating-effect tending to change said timing-device from a first one of its operational conditions to its second operational condition, means responsive to the glowing operation of the grid-glow tube for counteracting said first actuating-effect and developing a second actuating-effect tending to change said timing-device in the opposite direction, means for making a lowering adjustment of said voltage-regulating means when said timing-device reaches its first operational condition, and means for making a raising adjustment of said voltage-regulating means when said timing-device reaches its second operational condition.

7. Voltage-regulating equipment for an electrical load-device having a desirable operating-range in which a predetermined rate of occurrence of predetermined, randomly recurrent, transient, voltage-responsive increases in the magnitude of the load-current is maintained between predetermined limits, comprising a supply-circuit for said load-device, voltage-regulating means associated with said supply-circuit, a cold-cathode grid-glow tube, direct-current energizing-means for its anode-cathode circuit, means for providing an independently variable unidirectional grid-biasing voltage, means for developing a grid-biasing voltage responsive to the load-current of the load-device, circuit-means for serially combining both of said grid-biasing voltages and for so applying the resultant voltage to the grid of the grid-glow tube as to cause a glow therein upon the attainment of an instantaneous current-magnitude of a predetermined value in said load-device, timing-means responsive to the glowing of the grid-glow tube for subsequently interrupting the glowing operation thereof, a timing-device having two different operational conditions, means for normally developing a first actuating-effect tending to change said timing-device from a first one of its operational conditions to its second operational condition, means responsive to the glowing operation of the grid-glow tube for counteracting said first actuating-effect and developing a second actuating-effect tending to change said timing-device in the opposite direction, means for making a lowering adjustment of said voltage-regulating means when said timing-device reaches its first operational condition, and means for making a raising adjustment of said

voltage-regulating means when said timing device reaches its second operational condition.

8. Voltage-regulating equipment for an electrical load-device having a desirable operating-range in which a predetermined rate of occurrence of predetermined, randomly recurrent, transient, voltage-responsive current-increases is maintained between predetermined limits, comprising a supply-circuit for said load-device, voltage-regulating means associated with said supply-circuit, means for obtaining discrete current-responses to said transient current-increases, means for prolonging said discrete current-responses for short predetermined times, said short predetermined times being less than the longest expectable time-interval between successive transient current-increases, a timing-relay having an actuating-coil and a biasing-means opposing the actuating-force produced by said actuating-coil, means for electrically energizing said actuating-coil from across said supply-circuit with an amount of energization which normally causes the actuating-force of the coil to predominate in such manner as to tend to cause the timing-relay to move from a non-actuated position to an actuated position at a first predetermined speed, means responsive to each of said prolonged discrete current-responses for temporarily causing the biasing-force to predominate in said timing-relay so as to tend to cause the timing-relay to move in the opposite direction at a second predetermined speed, said first and second predetermined speeds being both so slow that said timing-relay moves through only a part of the distance between its aforesaid positions during one of said short predetermined times, means for adjusting at least one of the factors determining the part of the distance between said positions during which said timing-relay moves during one of said short predetermined times in at least one of the directions of movement of said timing-relay, means for making a lowering adjustment of said voltage-regulating means when said timing-relay is in its non-actuated position, and means for making a raising adjustment of said voltage-regulating means when said timing-relay is in its actuated position.

9. Voltage-regulating equipment for an electrical load-device having a desirable operating-range in which a predetermined rate of occurrence of predetermined, randomly recurrent, transient, voltage-responsive increases in the magnitude of the load-current is maintained between predetermined limits, comprising a supply-circuit for said load-device, voltage-regulating means associated with said supply-circuit, means quickly responsive to any and all increases in the magnitude of the load-current beyond a predetermined value for obtaining predetermined discrete current-responses, short-time means for insuring that each of said discrete current-responses shall last for at least a short predetermined time which is less than the longest expectable time-interval between successive transient current-increases, a timing-relay having an actuating-coil and a biasing-means opposing the actuating-force produced by said actuating-coil, means for electrically energizing said actuating-coil from across said supply-circuit with an amount of energization which normally causes the actuating-force of the coil to predominate in such manner as to tend to cause the timing-relay to move from a non-actuated position to an actuated position at a first predetermined speed, means responsive to each of said prolonged discrete current-responses

for temporarily causing the biasing-force to predominate in said timing-relay so as to tend to cause the timing-relay to move in the opposite direction at a second predetermined speed, means for making a lowering adjustment of said voltage-regulating means when said timing-relay is in its non-actuated position, and means for making a raising adjustment of said voltage-regulating means when said timing-relay is in its actuated position.

10. Voltage-regulating equipment for an electrical load-device subject to transient current-increases randomly recurring at a rate and with an intensity dependent upon the voltage, comprising a supply-circuit for said load-device, voltage-regulating means associated with said supply-circuit, a timing-relay having an actuating-coil and a biasing-means opposing the actuating-force produced by said actuating-coil, means for electrically energizing said actuating-coil from across said supply-circuit with an amount of energization which normally causes the actuating-force of the coil to predominate in such manner as to tend to cause the timing-relay to move from a non-actuated position to an actuated position at a predetermined speed, current-responsive transient-summarizing means for at times causing the biasing-force to predominate in said timing-relay so as to tend to cause the timing-relay to move in the opposite direction at a current-responsive speed which is so slow, at times, as to require a plurality of transient current-increases to occur before the timing-device-relay moves all the way from its actuated position to its non-actuated position, means for making a lowering adjustment of said voltage-regulating means when said timing-relay is in its non-actuated position, and means for making a raising adjustment of said voltage-regulating means when said timing-relay is in its actuated position.

11. Voltage-regulating equipment for an electrical load-device subject to transient current-increases randomly recurring at a rate and with an intensity dependent upon the voltage, comprising a supply-circuit for said load-device, voltage-regulating means associated with said supply-circuit, a timing-relay having an actuating-coil and a biasing-means opposing the actuating-force produced by said actuating-coil, means for electrically energizing said actuating-coil from across said supply-circuit with an amount of energization which normally causes the actuating-force of the coil to predominate in such manner as to tend to cause the timing-relay to move from a non-actuated position to an actuated position, means responsive to the load-current of the load-device for at times causing the biasing-force to predominate in said timing-relay so as to tend to cause the timing-relay to move in the opposite direction, means for making a lowering adjustment of said voltage-regulating means when said timing-relay is in its non-actuated position, and means for making a raising adjustment of said voltage-regulating means when said timing-relay is in its actuated position.

12. Voltage-regulating equipment for an electrical load-device, comprising a supply-circuit for said load-device, voltage-regulating means associated with said supply-circuit, a timing-relay having an actuating-coil and a biasing-means opposing the actuating-force produced by said actuating-coil, means for electrically energizing said actuating-coil from across said supply-circuit with an amount of energization which normally causes the actuating-force of the coil to

predominate in such manner as to tend to cause the timing-relay to move from a non-actuated position to an actuated position, means responsive to the load-current of the load-device for at times causing the biasing-force to predominate in said timing-relay so as to tend to cause the timing-relay to move in the opposite direction, means for making a lowering adjustment of said voltage-regulating means when said timing-relay is in its non-actuated position, and means for making a raising adjustment of said voltage-regulating means when said timing-relay is in its actuated position.

13. Voltage-regulating equipment for an electrical load-device subject to transient current-increases randomly recurring at a rate and with an intensity dependent upon the voltage, comprising a supply-circuit for said load-device, voltage-regulating means associated with said supply-circuit, a cold-cathode grid-glow tube, direct-current energizing-means for its anode-cathode circuit, means for developing transient grid-biasing voltages responsive to load-device current-increases of a predetermined intensity and for so applying said grid-biasing voltages to the grid of the grid-glow tube as to cause said grid-glow tube to glow, timing-means responsive to the glowing of the grid-glow tube for subsequently interrupting the glowing operation thereof, and means responsive to the glowing operation of said grid-glow tube tending to produce a lowering adjustment of said voltage-regulating means.

14. Voltage-regulating equipment for an electrical load-device subject to transient current-increases randomly recurring at a rate and with an intensity dependent upon the voltage, comprising a supply-circuit for said load-device, voltage-regulating means associated with said supply-circuit, a timing-relay having an actuating-coil and a biasing-means opposing the actuating-force produced by said actuating-coil, means for electrically energizing said actuating-coil from across said supply-circuit with an amount of energization which normally causes the actuating-force of the coil to predominate in such manner as to tend to cause the timing-relay to move from a non-actuated position to an actuated position, means for translating those transient load-device current-increases which are of a predetermined magnitude into discrete time-controlled impulses of a predetermined magnitude and for utilizing said impulses to temporarily cause the biasing-force to predominate in said timing-relay so as to tend to cause the timing-relay to move in the opposite direction, and means responsive to the non-actuated position of said timing-relay for producing a lowering adjustment of said voltage-regulating means.

15. Voltage-regulating equipment for an electrical load-device subject to transient current-increases randomly recurring at a rate and with an intensity dependent upon the voltage, comprising, in combination; a supply-circuit for supplying energy to said load-device; voltage-regulating means associated with said supply-circuit; a source of unidirectional potential; a space-current arcng-device of a type having an anode-cathode arcng-space which is normally substantially non-conducting, starting control means for initiating the conductive operation of said anode-cathode arcng-space, said space-current arcng-device being of a type in which the anode-cathode current, once started, will remain flowing, independently of the subsequent condition of said starting control means, as long as any substantial

75

unidirectional voltage is applied to said anode-cathode arcing-space; circuit-connection means for establishing a main direct-current circuit serially including said unidirectional-potential source and the anode-cathode circuit of said space-current arcing-device; means responsive to the load-current of the load-device for causing said starting control means to be operatively energized upon the attainment of an instantaneous current-magnitude of a predetermined value in said load-device; timing-means responsive to the anode-cathode current of the space-current arcing-device for subsequently interrupting the current-carrying operation thereof after a short predetermined time; a timing-device having two different operational conditions; means for normally developing a first actuating-effect tending to change said timing device from a first one of its operational conditions to its second operational condition; current-responsive means including a response to the anode-cathode circuit of said space-current arcing-device for at times counteracting said first actuating-effect and developing a second actuating-effect tending to change said timing-device in the opposite direction at a speed which is so slow, at times, as to require a plurality of transient current-increases to occur before the timing-device is completely changed from its second operational condition to its first operational condition; means for making a lowering adjustment of said voltage-regulating means when said timing-device reaches its first operational condition; and means for making a raising adjustment of said voltage-regulating

means when said timing-device reaches its second operational condition.

16. Voltage-regulating equipment for an electrical load-device subject to transient current-increases randomly recurring at a rate and with an intensity dependent upon the voltage, comprising, in combination; a supply-circuit for said load-device; voltage-regulating means associated with said supply-circuit; a space-current arcing-device of a type having an anode-cathode arcing-space which is normally substantially non-conducting, starting control means for initiating the conductive operation of said anode-cathode arcing-space, said space-current arcing-device being of a type in which the anode-cathode current, once started, will remain flowing, independently of the subsequent condition of said starting control means, as long as any substantial unidirectional voltage is applied to said anode-cathode arcing-space; direct-current energizing-means for the anode-cathode circuit of said space-current arcing-device; means responsive to load-device current-increases of a predetermined intensity for causing said starting control means to be operatively energized; timing-means responsive to the anode-cathode current of said space-current arcing-device for subsequently interrupting the current-carrying operation thereof; and means responsive to the anode-cathode current of said space-current arcing-device for producing a lowering adjustment of said voltage-regulating means.
